UNITED STATES PATENT OFFICE

WALTER J. KOHLER, JR., AND FRANK G. BROTZ, OF KOHLER, WISCONSIN

DESIGN FOR A LAVATORY

Application filed November 14, 1932. Serial No. 45,984. Term of patent 14 years.

To all whom it may concern:

Be it known that we, WALTER J. KOHLER, Jr., and FRANK G. BROTZ, citizens of the United States, residing at Kohler, in the county of Sheboygan and State of Wisconsin, have invented a new, original, and ornamental Design for Lavatories, of which the following is a specification, reference being

had to the accompanying drawing, forming part thereof. The figure is a perspective view of the lavatory showing our new design.

We claim:

The ornamental design for a lavatory, as shown.

WALTER J. KOHLER, JR.
FRANK G. BROTZ.
